ELEVATOR SYSTEMS TRANSFERABLE BETWEEN MODES OF OPERATION

John Suozzo, Paramus, and Allen A. Rosenkrans, Summit, N. J., assignors to Westinghouse Electric Corporation, East Pittsburgh, Pa., a corporation of Pennsylvania

Application March 30, 1953; Serial No. 345,648

12 Claims. (Cl. 187—29)

This invention relates to elevator systems and it has particular relation to elevator systems arranged for operation with or without elevator attendants.

In elevator systems it is common practice to provide call registering means for registering calls for floors at which elevator car is to stop. Such call registering means may include car-call registering means which are operable from within an elevator car for the purpose of registering calls for floors desired by passengers within the elevator car. In addition, floor-call registering means may be provided for the purpose of permitting prospective passengers at the various floors of a structure to register calls for elevator service. Floor-call registering means may include up-floor-call registering means which may be operated if elevator service in the up direction is desired. In addition, down-floor-call registering means may be provided for operation by prospective passengers if elevator service in the down direction is desired.

If an elevator system is designed for operation without attendants, an elevator car automatically departs from a floor at which it has stopped following closure of the elevator car doors. During its operation the elevator car stops at each floor for which a call for service is registered which may be answered by the elevator car.

If the elevator system is arranged for operation with attendants, an elevator car can depart from a floor at which it has stopped only following a manual operation performed by the elevator car attendant who is located within the car.

In accordance with the invention an elevator system is arranged for operation with or without attendants. To this end a transfer device is provided which may be actuated for the purpose of transferring the system from a condition wherein it operates without attendants to a condition wherein it is operated with attendants.

If the transfer from operation without attendants to operation with attendants is effected while an elevator car is stopped at an intermediate floor for the purpose of discharging its last passenger, an attendant may proceed to such floor for the purpose of entering the elevator car and moving the elevator car away from the floor. To facilitate entry of the attendant into the elevator car, the invention provides that the actuation of the transfer device can result in a transferring operation only after the elevator car has proceeded to a predetermined floor. With such an arrangement the attendant may remain on the predetermined floor with the assurance that the elevator car will proceed to his floor before the transferring operation is completed.

If desired the transfer device also introduces a further alteration in the operation of the elevator system. For example, when the elevator system is placed under the control of attendants, an elevator car may be prevented from responding to calls registered by the floor-call registering means.

It is therefore an object of the invention to provide

2

an improved elevator system arranged for operation selectively with or without attendants.

It is a further object of the invention to provide an elevator system arranged for operation selectively with or without attendants wherein the transfer from one to another of the types of operation may be completed only at a predetermined floor.

Other objects of the invention will be apparent from the following discussion taken in conjunction with the accompanying drawings in which:

Figures 1, 2 and 3 are schematic views with circuits shown in straight-line form of portions of an elevator system embodying the invention.

Figs. 1A, 2A and 3A are key representations of electromagnetic relays and switches employed in the system of Figs. 1, 2 and 3. If Figs. 1A, 2A and 3A are placed in horizontal alignment respectively with Figs. 1, 2 and 3 it will be found that corresponding coils and contacts of the electromagnetic relays and switches of the two sets of figures will be substantially in horizontal alignment; and

Fig. 4 is a view in front elevation with parts shown schematically of an elevator car employed in the system of Figs. 1, 2 and 3.

In order to simplify the presentation of the invention a number of conventions have been adopted. Although the invention may be applied to an elevator system having any desired number of cars and serving a structure having any desired number of floors, the invention can be described adequately with reference to a system having two elevator cars serving a structure having eleven floors. The two cars are identified by the reference characters A and B.

Since the circuits for the two cars A and B are similar, the invention will be described primarily with reference to the elevator car A. Similar components for the elevator car B will be identified by the same reference characters employed for the corresponding components associated with elevator car A preceded by the letter B. For example, the reference characters U and BU designate respectively the up switches for the elevator cars A and B.

The various electromagnetic relays and switches each may have several contacts. A relay or switch will be identified by the reference character for the relay or switch followed by a numeral specific to the set of contacts. Thus, the reference characters U1 and U3 designate the first and third sets of contacts for the up-switch U associated with the elevator car A.

A relay or switch may have make or front contacts which close when the relay or switch is energized and picked up and which are open when the relay or switch is deenergized and dropped out. A relay or switch also may have back or break contacts which are closed when the relay or switch is deenergized and dropped out and which are open when the relay or switch is energized and picked up.

To facilitate the presentation of the invention certain apparatus of the elevator system is listed as follows:

Apparatus for elevator car A

V	Speed relay.
U	Up-switch.
M	Running relay.
D	Down-switch.
E	Inductor slowdown relay.
F	Inductor stopping relay.
G	Holding relay.
W	Up-direction relay.
X	Down-direction relay.
70T	Non-interference relay.
DR	Door safety relay.
80	Manual start relay.
T	Car-call stopping relay.

Apparatus for elevator car A—Continued

1CR to 11CR	Car-call registering relays.
S	Floor-call stopping relay.
J	High-call reversal relay.
45	Door control relay.
IS	In-service switch.
TR	Car transfer switch.

Apparatus common to all cars

1UR to 10UR	Up-floor-call registering relays.
2DR to 11DR	Down-floor-call registering relays.
N	Bank transfer relay.

Referring to the drawings, Fig. 1 shows the elevator car A which is connected to a counterweight 10 through one or more flexible ropes or cables 11 passing over a sheave 12. The sheave 12 is secured to a shaft 13 which also carries a brake drum 14 and the armature 15A of a motor 15 employed for moving the elevator car. Although various types of motors and motor control systems may be employed, it will be assumed that the motor 15 is a direct current motor having a field winding 15F which is connected across two buses L1 and L2 for energization. The buses L1 and L2 represent a source of direct-current electric energy.

It will be assumed that the control for the electric motor 15 is a variable-voltage control which includes a direct-current generator 16 having an armature 16A, a series field winding 16S and a separately-excited field winding 16F. By inspection of Fig. 1 it will be noted that the armatures 15A and 16A and the series field winding 16S are connected in series in a loop circuit.

The brake drum 14 has associated therewith a spring-applied electromagnetically-released brake shoe 14S of conventional design. The brake shoe is released from the brake drum upon energization of a brake coil 17. This brake coil is connected for energization across the buses L1 and L2 through make contacts U1 or make contacts D1 of the up-switch U or the down-switch D.

Because of the large number of circuits which are controlled in accordance with the movement of the elevator car, it is conventional to provide the system with a floor selector FS. The floor selector includes a panel FSP on which rows of contact segments are mounted. The contact segments are insulated from each other. Although a large number of rows of contact segments are provided only two of these rows are illustrated in Fig. 1. One of the rows illustrated in Fig. 1 includes contact segments a1 to a11. The second row illustrated includes the contact segments b1 to b11.

The panel FSP has associated therewith a carriage FSC which moves across the panel in accordance with movement of the elevator car A but at a greatly reduced speed. To this end the carriage FSC is coupled to the shaft 13 through suitable gearing 18. Consequently, the carriage moves vertically as viewed in Fig. 1 in accordance with vertical movements of the elevator car A.

The carriage FSC carries a separate brush for each of the rows of contact segments. For example, the carriage has a brush aa which successively engages the contact segments a1 to a11 as the elevator car moves from the first to the eleventh floor of the structure. Similarly, the brush bb is carried by the carriage and successively engages the contact segments b1 to b11. Circuits are associated with the brushes and contact segments for the purpose of controlling the operation of the elevator car A.

The direction and speed of movement of the elevator car A are determined by the direction and magnitude of the energization of the field winding 15F. This field winding is connected across the buses L1 and L2 through a resistor RE1 and contacts of a reversing switch. The reversing switch includes make contacts U2 and U3 of the up-switch U. These contacts are closed to energize the field winding with proper polarity for up travel of the elevator car A. The field winding also may be energized through make contacts D2 and D3 which are closed to

energize the field winding with proper polarity for down travel of the elevator car. Closure of make contact V1 of a speed relay V shunts the resistor RE1 to increase the speed of the elevator car.

- 5 Mounted for movement with the elevator car A are an inductor slowdown relay E and an inductor stopping relay F which may be of conventional construction. For example, the inductor slowdown relay E has two break contacts E1 and E2. For the break contacts E1 to open, two conditions must be satisfied. The coil of the inductor slowdown relay E must be energized and the relay must be adjacent an inductor plate UEP. One of the inductor plates UEP is associated with each of the floors at which the elevator car A is to stop while traveling in the up direction.

When the elevator car while traveling in the up direction is to stop at a floor which it is approaching the coil of the inductor slowdown relay E is energized. When the inductor relay E reaches the inductor plate UEP associated with such floor, a magnetic circuit is completed which results in opening of the break contacts E1. The contacts E1 thereafter may remain open until the coil E is deenergized.

- In a similar manner, an inductor plate DEP is associated with each of the floors at which the elevator car A may stop while traveling in the down direction. If the elevator car A is to stop at a floor while traveling in the down direction, the coil of the inductor slowdown relay E is energized. When the inductor relay reaches the inductor plate DEP associated with such floor, the break contacts E2 open and remain open until the coil is deenergized.

The inductor stopping relay F is similar in construction to the inductor slowdown relay E and is similarly associated with inductor plates UFP and DFP. It will be understood that an inductor plate UFP is associated with each of the floors at which the elevator car A may stop while traveling in the up-direction. One of the inductor plates DFP is associated with each of the floors at which the elevator car may stop while traveling in the down-direction.

- As the elevator car approaches a floor at which it is to stop, the inductor slowdown relay E opens one of its sets of contacts a suitable distance in advance of the floor to initiate a slowdown operation of the elevator car A. The elevator car A then continues to approach the desired floor at a reduced speed until the inductor stopping relay F opens one of its sets of contacts to stop the elevator car accurately at such floor.

When the elevator car A is traveling in the up-direction, the speed relay V is energized through make contacts U4 of the up-switch U, a limit switch 20 and the break contacts E1 of the inductor slowdown relay E. The limit switch 20 is biased into closed condition and is cam-operated to open as the elevator car reaches its upper limit of travel.

- If the elevator car A is set for travel in the down direction, the speed relay V is energized through make contacts D4 of the down switch D, a limit switch 21 and break contacts E2 of the inductor slowdown relay. The limit switch 21 is biased into closed condition and is cam-operated to open as the elevator car A reaches its lower limit of travel.

To permit registration of calls for floors desired by passengers within the elevator car or by a car attendant, push buttons 1C to 11C are located within the elevator car A. Circuits associated with these push buttons will be discussed below.

- Floor calls are registered by operation of suitable push buttons located at the various floors. For example, a push button 2U is located at the second floor. A similar push button identified by the letter U preceded by a numeral designating a floor is located at each floor from which a prospective passenger may desire to travel in the up-direction. For down service a push button 2D is

located at the second floor. A similar push button identified by the letter D preceded by a floor-designating numeral is located at each floor from which a prospective passenger may desire to travel in the down direction.

It will be understood that the elevator car A may be provided with doors which are operated in any conventional manner. Thus the doors may be manually opened and manually closed. They may be biased towards closed position and manually opened against such bias or they may be power-operated in both directions.

A suitable door operator is represented in Fig. 4 for the elevator car A. By reference to Fig. 4 it will be noted that the elevator car is provided with a door 22 which is in its closed position. The door is opened and closed by means of an arm 22A which is rotated by a motor 22M through suitable gearing. The arm 22A has its free end pivotally connected to a link 22L which in turn is pivotally connected to the door 22. The motor 22M may be a direct-current motor which is energized through a reversing switch. It will be assumed that the motor has a permanent-magnet field and that operation of the reversing switch controls the direction of the rotation of the motor to open and close the door 22. The reversing switch comprises contacts on the door-control relay 45. Break contacts of this relay connect the motor for energization with proper polarity to open the door. Make contacts of the relay connect the motor for energization with proper polarity to close the door. A cam-operated switch 22S is biased towards open condition and is positioned to be closed as the door reaches its fully-closed position.

The elevator car A is provided with a running relay M which can be energized only if make contacts DR1 of a door safety relay DR are closed to indicate that all doors associated with the elevator car A are closed. This would include hoistway doors if such doors are employed. Energization of the running relay M also is accompanied by energization of either the up switch U or the down switch D. If the car is set for up travel, the make contacts W1 of an up-direction relay are closed. Under these circumstances the up switch U and the running relay M are energized as follows:

L1, 70T1 or 80—1, W1, F1, 23, U, M, DR1, L2

The break contacts 70T1 are associated with a non-interference relay 70T and are effective when the system is arranged for operation without attendants. The make contacts 80—1 are effective for starting the elevator car A when the car A is arranged for operation with an attendant. The limit switch 23 is biased into closed condition and is cam-operated to open as the elevator car reaches its upper limit of travel. When the up switch U picks up it closes its make contacts U5 to establish a holding circuit around the make contacts W1 and the contacts 70T1 and 80—1.

In somewhat similar manner the running relay M may be energized when the elevator car A is set for down travel through the following circuit:

L1, 70T1 or 80—1, X1, F2, 24, D, M, DR1, L2

The limit switch 24 is biased into closed condition and is cam-operated to open as the elevator car reaches its lower limit of travel. When the down switch D picks up, make contacts D5 close to establish a holding circuit around the contacts X1, 80—1 and 70T1.

To permit energization of the holding relay G, inductor slowdown relay E and the inductor stopping relay F, make contacts M1 of the running relay must be closed. In addition, one of the sets of make contacts T1, J1 and S1 must be closed. The make contacts T1 are closed when the elevator car A is to stop at a floor in response to a registered car call. The make contacts J1 are closed when no calls remain to be answered by the elevator car A for floors above the position of the elevator car. The make contacts S1 are

closed when the elevator car A is to stop at a floor in response to a registered floor call. These three sets of contacts may be shunted by make contacts G1 of the holding relay G.

5 The up-direction relay W is energized as follows:

L1, D6, X2, J2, W, 25, L2

The limit switch 25 is biased to closed condition and is cam-operated to open as the elevator car A reaches its upper limit of travel. When the running relay M picks up, make contacts M2 close to shunt the break contacts J2.

The down direction relay is energized through the circuit:

15

L1, U6, W2, X, 26, L2

The limit switch 26 is biased to closed condition and is cam-operated to open as the elevator car reaches its lower limit of travel.

20 The non-interference relay 70T may be energized either through the make contacts M3 of the running relay M or through break contacts TR1 of a car transfer switch TR. This relay has a time delay in drop-out which may be provided in any suitable manner. For present purposes it will be assumed that the time delay is obtained by connecting a resistor RE2 across the coil of the relay 70T. If the elevator car A stops at a floor while it is conditioned for operation without an attendant, the elevator can not be dispatched from the floor until the non-interference relay 70T drops out to close its break contacts 70T1.

25 The door safety relay DR is energized through the safety switch 22S and through similar safety switches used for hoistway doors associated with the elevator car A if such hoistway doors are provided. It will be understood that the door safety relay DR can be energized and picked up only if all of the doors associated with the elevator car are in closed condition.

30 If the elevator car A is arranged for operation by a car attendant, the break contacts TR2 are closed to permit energization therethrough of the manual start relay 80. The energizing circuit for this relay is completed through a car switch 80S which is located within the elevator car A.

35 In the upper part of Fig. 2 circuits are illustrated for registering car calls. Since the circuits associated with the various floors are similar, such circuits are illustrated in Fig. 2 only for the first, second, third, tenth and eleventh floors. The car-call buttons 1C to 11C have associated therewith car-call registering relays 1CR to 11CR and contact segments a1 to a11 and b1 to b11 which are associated with the floor selector FS of Fig. 1. When any of the car-call buttons is actuated, an energizing circuit is completed for its associated car call registering relay through one of the sets of make contacts W3 or X3. For example, if the elevator car is set for up travel, the make contacts W3 are closed. Upon operation of the car-call push button for the third floor the following circuit is established:

40

L1, 3C, 3CR, W3, L2

45 When energized, the car-call registering relay 3CR closes its make contacts 3CR1 to establish a holding circuit around the push button 3C. In addition, the closed contacts connect the contact segments a3 and b3 to the bus L1.

50 Assuming that the elevator car A is proceeding in the up direction, the make contacts W4 and M4 are closed. Before the elevator car A reaches the third floor, the brush aa reaches the contact segment a3 and the engagement of the brush and segment completes an energizing circuit for the car-call stopping relay T. This relay then initiates a stopping operation of the elevator car A at the third floor. As the car stops the brush aa may pass slightly beyond the contact segment a3.

55 Had the elevator car A been set for down travel, the

make contacts X3, X4 and M4 would be closed. If the elevator car A approaches the third floor under such circumstances and with a car-call registered for the third floor, the engagement of the brush *bb* with the contact segment *b3* (which occurs before the elevator car A reaches the third floor) would complete an energizing circuit for the car-call stopping relay T. As the elevator car A reaches its limit of travel in either direction, the make contacts W3 and X3 would be momentarily open to reset any of the energized car-call registering relays 10 1CR to 11CR.

The lower portion of Fig. 2 illustrates the floor-call registering circuits for the elevator cars. Because of the similarity of the circuits, up-floor-call circuits are illustrated only for the first, second and third floors and down-floor-call circuits are illustrated only for the second, third, ninth, tenth and eleventh floors.

Floor-call circuits for stopping an up-traveling elevator car A are associated with contact segments *c2* to *c11* and *d2* to *d11* which are incorporated in the floor selector FS of Fig. 1. Let it be assumed that a floor call is registered by operation of the floor push button 3U by a prospective passenger at the third floor. Such operation of the push button results in energization of the floor-call registering relay 3UR. This relay closes its make contacts 3UR1 to establish a holding circuit around the push button 3U. The closure of the make contacts 3UR1 connects the contact segment *c3* for the elevator car A and the contact segment *Bc3* for the elevator car B to the bus L1. If the elevator car A is traveling up, the make contacts W5 are closed and it will be assumed that the make contacts IS1 are closed. As the elevator car A nears the third floor the brush *cc* engages the contact segment *c3* to complete an energizing circuit for the floor-call stopping relay S. This relay then initiates a stopping operation of the elevator car. As the elevator car stops the brush *cc* may pass slightly beyond the contact segments *c3*. Had the elevator car B answered the call at the third floor the engagement of the brush *Bcc* with the contact segment *Bc3* would have completed an energizing circuit for the relay BS.

As the elevator car A stops at the third floor the brush *dd* engages the contact segment *d3* to complete the following circuit:

L1, 3UR1, 3URN, *d3*, *dd*, W6, M5, IS1, L2

The coil for the relay 3UR and the cancelling coil 3URN are energized to produce magnetomotive forces acting in opposition to each other, the coils being wound on the same core. Consequently, the energization of the cancelling coil 3URN resets the relay 3UR. Had the elevator car B answered the call at the third floor, its brush *Bdd* would have engaged the contact segment *BD3* to complete an energizing circuit for the cancelling coil 3URN.

The floor-call registering circuits associated with the up push buttons for the remaining floors will be understood from the discussion of the circuits for the third floor. Since the push button 11D is intended to stop an uptraveling elevator car at the upper terminal floor, the circuits associated therewith are similar to those associated with the push button 3U.

The floor-call circuits for stopping a down traveling elevator car have associated therewith contact segments incorporated in the floor selectors. For example, these circuits have associated therewith the contact segments *e1* to *e10* and *f1* to *f10* which are incorporated in the floor selector FS of Fig. 1.

Let it be assumed that a prospective passenger at the third floor operates the push button 3D to register a down-floor call. Such operation connects the down-floor call registering relay 3DR for energization and this relay closes its make contacts 3DR1 to establish a holding circuit around the push button. In addition, the make contacts 3DR1 connect the contact segments *f3* to the bus L1. Contact segment *Bf3* also is connected through the make

5 contacts 3DR1 to the bus L1. If the elevator car A is traveling down, the make contacts X5 and X6 are closed and it is assumed that the make contacts IS1 are closed. As the elevator car nears the third floor, the brush *ff* engages the contact segments *f3* to complete the following circuit:

L1, 3DR1, *f3*, *ff*, X5, S, IS1, L2

The energized floor-call stopping relay S now initiates a stopping operation of the elevator car A at the third floor. As the elevator car stops, the brush *ff* may pass slightly beyond the contact segment *f3*.

As the elevator car A stops at the third floor, the brush *ee* engages the contact segment *e3* to complete the following cancelling circuit:

L1, 3DR1, 3DRN, *e3*, *ee*, X6, M5, IS1, L2

The cancelling coil 3DRN acts in opposition to the coil of the relay 3DR for the purpose of resetting the relay. The down-floor-call registering circuits associated with the remaining floors operate in a similar manner and will be understood from the discussion of the operation of the circuits associated with the push button 3D.

Since the up-floor push button 1U for the first floor is intended to stop a down-traveling elevator car, it is associated with contact segments in the *e* and *f* rows of the floor selector. Although it is labeled an up push button, it operates in the same manner as the push button 3D to stop a down-traveling elevator car.

The upper part of Fig. 3 illustrated circuits for initiating a reversal of an up-traveling elevator car if no calls remain above the elevator car which can be answered by such car. As shown in Fig. 3, a call-above circuit 30 is provided which includes in series break contacts of all of the floor-call registering relays and of all the car-call registering relays for the elevator car A for floors above the first floor. The circuit 30 is associated with the row of contact segments *g2* to *g11* which are located in the floor selector FS of Fig. 1. The contacts of the floor-call registering relays and car-call registering relays for floors above the position of the elevator car A are located in the circuit 30 above the position of the brush *gg*.

The high call reversal relay J is connected through make contacts W7 of the up-direction relay W and make contacts IS2 of the in-service switch IS between the brush *gg* and the bus L2.

Let it be assumed that the elevator car during up travel is approaching the tenth floor, the make contacts W7 and IS2 are assumed to be closed. It will be noted that the contact segment *g10* for the tenth floor is connected to the bus L1 through the break contacts 10UR2, 11CR2 and 11DR2. If these contacts are all closed, the engagement of the brush *gg* with the contact segment *g10* results in energization of the high-call reversal relay J and this relay picks up to initiate a reversal of the elevator car A at the tenth floor. However, if any of these three sets of break contacts is open, it follows that a call is registered requiring travel of the elevator car above the tenth floor. Under such circumstances the high-call reversal relay J can not be energized and the elevator car proceeds to serve the registered call for the higher floor.

As a further example, the contact segment *g9* is connected to the bus through the break contacts 9UR2, 10CR2, 10DR2, 10UR2, 11CR2 and 11DR2. These contacts are associated with all of the call registering relays which can be answered only by travel of the elevator car above the ninth floor. Let it be assumed that none of these relays has been energized to register a call. Under such circumstances, if the elevator car A is traveling up towards the ninth floor, the engagement of the brush *gg* with the contact segments *g9* completes an energizing circuit for the high-call reversal relay J. However, had a call been registered requiring further up travel of the elevator car such as a car-call

for the eleventh floor, the break contacts 11CR2 would be open to prevent energization of the high-call reversal relay J and the elevator car A would continue its upward motion to serve the registered car-call for the eleventh floor.

Break contacts of the call registering relays and contact segments located between the contact segments g4 and g9 are not illustrated in Fig. 3 but the disposition of these additional contact segments and contacts in the circuit 30 will be understood from the foregoing discussion and the illustration of the remainder of the circuit.

As previously explained, the elevator car door is controlled by the door-control relay 45. The relay 45 is connected for energization through the normally closed switch 31, and through make contacts 80-2 when the elevator car is on attendant operation or break contacts 70T2 when the elevator car is on non-attendant operation. The switch 31 may be located in the elevator car A and may be manually operated before the elevator car door is completely closed to reopen the door.

Upon energization the door control relay 45 closes its make contacts 45-1 to partly complete a holding circuit which is completed through the make contacts M6 of the running relay.

When the elevator car A is in service, the manually-operated switch 32 is closed to connect the in-service relay IS for energization. When energized, the relay closes the make contacts IS3 to complete with the limit switch 33 a holding circuit around the manually-operated switch 32. The limit switch 33 is biased to its closed condition and is designed to be cam-operated to open when the elevator car reaches a predetermined floor such as the first floor. Consequently, if the switch 32 is opened while the elevator car is away from the first floor, the elevator car will remain in service until it reaches the first floor to open the limit switch 33, which, in turn, opens the holding circuit for the in-service relay IS.

Preferably make contacts M7 of the running relay M are connected around the limit switch 33. With this provision, if the elevator car is in service it will remain in service until the switch 32 is opened, the limit switch 33 is opened (i. e. the car is at the first floor) and the contacts M7 are open (i. e. the car is not set to run).

By inspection of Fig. 3 it will be noted that the operation of the in-service switch IS to its pickedup condition results in closure of the make contacts IS4 to prepare car transfer switch TR for a subsequent energization.

As long as the car transfer switch TR is deenergized the elevator car A is arranged for attendant operation. If the manually-operable switch 34 is operated to complete with the make contacts IS4 an energizing circuit for the car transfer switch TR, the transfer switch TR then modifies the control circuits of the elevator car A for non-attendant operation.

In picking up, the car transfer relay TR closes its make contacts TR3 to complete with the limit switch 35 a holding circuit for the car transfer relay. The limit switch is biased to its closed condition and is cam-operated to open when the elevator car is adjacent to a predetermined floor such as the first floor. Consequently, once the elevator car A is placed on non-attendant operation it can not be restored to attendant operation unless the elevator car A is adjacent the first floor to open the switch 35.

In order to control the transfer of the entire bank of elevator cars between attendant and non-attendant operation, a bank transfer relay N is arranged to be energized or deenergized by operation of a manually-operable switch 36. Thus if the elevator cars A and B are in-service, the make contacts IS4 and BIS4 are closed. If the manually-operable switch 36 is operated to energize the bank transfer relay N, the make contacts N1 and N2 are closed to complete energizing circuits for the car transfer relays

TR and BTR. Such energizations of car transfer relays places the elevator cars A and B both on non-attendant operation.

Although the response of the elevator system under various conditions may be ascertained from the drawings and from the foregoing discussion of the drawings, it will be helpful to consider some typical operations of the system. It will be assumed initially that the system is arranged for non-attendant operation. Under such circumstances the bank transfer relay N (Fig. 3) is energized. The in-service relays IS and BIS also are energized under the assumed conditions. Although the switches 34 and B34 are assumed to be open, the contacts N1, IS4, N2 and BIS4 are all closed and consequently the car transfer relays TR and BTR are picked up and energized.

Inasmuch as the in-service relay IS is picked up, the make contacts IS1 (Fig. 2) are closed and the elevator car A can respond to registered floor calls. Also make contacts IS2 (Fig. 3) are closed and the elevator car A consequently is conditioned to reverse when no call remains to be answered for a floor above the position of the elevator car A.

It will be assumed that the elevator car A is positioned at the first floor and that its doors are open. Under the assumed conditions the up direction relay W is energized. It will be noted that the break contacts TR1 (Fig. 1) are open and that non-interference relay 70T is under the control of the make contacts M3. The break contacts TR2 are open and the manual start relay 80 is ineffective for controlling the operation of the elevator car. Inasmuch as the door of the elevator car is assumed to be open, the switch 22S is open. It will be understood further that since the elevator car A is at the first floor, limit switches 21, 24, 26 (Fig. 1) 33 and 35 (Fig. 3) are open. The non-interference relay 70T is deenergized but it is assumed that this relay has not yet dropped out.

At this stage a passenger enters the elevator car A and operates the car-call push button 3C (Fig. 2). Since the make contacts W3 are closed, the operation of the car-call push button completes an energizing circuit for the car-call registering relay 3CR and this relay closes its make contacts 3CR1 to establish a holding circuit around the push button 3C. In addition, the break contacts 3CR2 (Fig. 3) in the call above circuit 30 open.

When the non-interference relay 70T (Fig. 1) times out it closes its break contacts 70T1 and 70T2 (Fig. 3). Closure of the break contacts 70T2 completes with the switch 31 an energizing circuit for the door control relay 45 and this relay picks up to connect the door motor 22M (Fig. 4) for energization with proper polarity to close the door 22. The relay 45 also closes its make contacts 45-1 (Fig. 3) to prepare partially a self-holding circuit.

As the door 22 (Fig. 4) reaches its fully closed position, it closes the switch 22S. By reference to Fig. 1 it will be noted that this switch is in circuit with the door safety relay DR. It will be assumed that all of the hoistway doors employed for the elevator car A are in closed condition and that the closure of the switch 22S completes an energizing circuit for the door safety relay DR. This relay closes its make contacts DR1 to complete with the closed contacts 70T1 of the non-interference relay the following circuit:

L1, 70T1, W1, F1, 23, U, M, DR1, L2

The up switch U is now energized and closes its make contacts U1 to energize the brake coil 17 for the purpose of releasing the elevator brake. In addition, make contacts U2 and U3 close to connect the field winding 16F for energization through the resistor RE1 with proper polarity for up travel of the elevator car A. Make contacts U4 close to complete with the limit switch 20 and the break contacts E1 an energizing circuit for the speed relay V. This relay closes its make contacts V1 to shunt the resistor RE1 and condition the elevator car A for full speed operation in the up direction. Closure of make

contacts U5 establishes a holding circuit around the contacts 70T1 and W1. Opening of the break contacts U6 has no immediate effect on the operation of the system.

The running relay M closes its make contacts M1 to prepare the relays G, E and F and for subsequent energization. Make contacts M2 establish a holding circuit around the contacts J2 of the high-call reversal relay J. Make contacts M3 close to energize the non-interference relay 70T.

Closure of the make contacts M4 (Fig. 2) and opening of the break contacts M5 have no immediate effect on the operation of the system. Closure of the make contacts M6 (Fig. 3) completes with the closed make contacts 45-1 a holding circuit for the door control relay 45.

It will be recalled that the closure of the make contacts M3 (Fig. 1) energizes the non-interference relay 70T. This relay upon energization opens its break contacts 70T1 and 70T2 (Fig. 3) without immediately affecting the operation of the system.

The departure of the elevator car A from the first floor results in closure of the limit switches 21, 24 and 26 (Fig. 1) and the limit switches 33 and 35 (Fig. 3). Such closures have no immediate effect on the operation of the elevator car A.

As the elevator car A proceeds at full speed towards the third floor, it is assumed that a prospective passenger at the tenth floor operates the down-floor call push button 10D (Fig. 2) to establish an energizing circuit for the down-floor call registering relay 10DR. The relay 10DR closes its make contacts 10DR1 to establish a self-holding circuit. In addition, the break contacts 10DR2 and 10DR3 (Fig. 3) open in the call-above circuits 30 and B30.

As the elevator car nears the third floor, the brush aa (Fig. 2) engages the contact segment a3 to complete the following circuit:

L1, 3CR1, a3, aa, W4, T, M4, L2

As a result of its energization, the car-call stopping relay T closes its make contacts T1 (Fig. 1) to complete with the closed make contacts M1 an energizing circuit for the relays G, E and F. The relay G now closes its make contacts G1 to establish a holding circuit around the contacts T1.

The elevator car A continues its approach towards the third floor and the slowdown inductor relay E finally comes into horizontal alignment with the inductor plate UEP for the third floor. This completes a magnetic circuit for the inductor relay E which results in opening of the break contacts E1 to deenergize the speed relay V. The speed relay V opens its make contacts V1 to introduce the resistor RE1 in series with the field winding 16F of the generator 16. The reduction in the energization of the field winding results in the slowing of the elevator car A to a landing speed.

The continued approach of the elevator car A at reduced speed toward the third floor brings the inductor stopping relay F into alignment with the inductor plate UFP for the third floor. This completes a magnetic circuit which results in opening of the break contacts F1 to deenergize the up switch U and the running relay M.

The up switch U opens its make contacts U1 to deenergize the brake coil 17 and permit reapplication of the spring-applied elevator brake. In addition, contacts U2 and U3 open to deenergize the generator field winding and the elevator car A consequently stops accurately at the third floor. Opening of the make contacts U4 and U5 and closure of the break contacts U6 have no immediate effect on the operation of the system.

The deenergization of the running relay M results in opening of the make contacts M1 to deenergize the relays G, E, F and these relays consequently reset without immediately affecting the operation of the system. Opening of the make contacts M2 has no immediate effect on the operation of the system.

Opening of the make contacts M3 results in deenergiza-

tion of the non-interference relay 70T and this relay now starts to time out. The time delay and drop out of the relay 70T should be sufficient to permit normal discharge or entry of passengers relative to the elevator car A.

Opening of the make contacts M4 interrupts the circuit for the car-call stopping relay T. As the elevator car A stops at the third floor, the brush aa passes slightly beyond the contact segment A3. Closure of the break contacts M5 has no immediate effect on the operation of the system.

Referring to Fig. 3 it will be observed that the opening of the make contacts M6 is accompanied by deenergization of the door-controlled relay 45. As shown in Fig. 4, the deenergization of the relay 45 connects the motor 22M for energization with proper polarity to open the door 22 of the elevator car A. The opening of the door is accompanied by opening of the switch 22S to deenergize the door safety relay DR (Fig. 1). The door safety relay DR opens its make contacts DR1 without immediately affecting the operation of the system.

It will be assumed that the passenger in the elevator car A now leaves. Upon the expiration of its time delay, the non-interference relay 70T drops out to initiate a starting operation of the elevator car A from the third floor in the same manner discussed with reference to the starting of the elevator car from the first floor.

The elevator car A now proceeds upwardly toward the tenth floor. As it approaches the tenth floor the brush gg (Fig. 3) reaches the contact segments g10 for the tenth floor. Under the assumed condition no call is registered requiring travel of the elevator car A above the tenth floor. Consequently, the engagement of the contact segment g10 by the brush gg completes the following circuit:

L1, 11DR2, 11CR2, 10UR2, g10, gg, W7, J, IS2, L2

The energized high call reversal relay J now closes its make contacts J1 (Fig. 1) to complete with the make contacts M1 an energizing circuit for the relays G, E and F. These relays operate to initiate the slow down and stopping of the elevator car at the tenth floor by the same sequence discussed for the stopping of the elevator car at the third floor.

In addition, the high-call reversal relay J opens its break contacts J2. Consequently, when the car stops and the make contacts M2 open, the up-direction relay W is deenergized. As the result of its deenergization the up-direction relay W opens its make contacts W1, W4 (Fig. 2), W5, W6 and W7 (Fig. 3) without immediately affecting the operation of the system. The closure of the break contacts W2 (Fig. 1) completes an energizing circuit for the down-direction relay X to condition the elevator car for operation in the down direction. This relay thereupon closes its make contacts X1 and opens its break contacts X2 without immediately affecting the operation of the system.

The make contacts X3 in Fig. 2 close, but slightly before such closing both of the contacts W3 and X3 are momentarily open, and such opening results in resetting of the car-call registering relay 3CR. This relay opens its make contacts 3CR1 and closes its make contacts 3CR2 (Fig. 3) without immediately affecting the operation of the system.

The down-direction relay also closes its make contacts X4 and X5 to further prepare the elevator car A for down travel.

By reference to Fig. 2 it will be noted that the closure of the make contacts X6 completes the following circuit:

L1, 10DR1, 10DRN, e10, ee, X6, M5, IS1, L2

The energization of the cancelling coil 10DRN resets the down-floor-call registering relay 10DR. This relay opens its make contacts 10DR1 and closes its break contacts 10DR2 (Fig. 3) and 10DR3 without immediately affecting the operation of the system.

It will now be assumed that the prospective passenger

at the tenth floor enters the elevator car and registers a car call by operating the push button 1C for the first floor. As a result of such operation, the car-call registering relay 1CR is connected for energization through the make contacts X3. The energized relay 1CR closes its make contacts 1CR1 to establish a holding circuit around the relay 1C.

Upon the expiration of its drop-out time, the non-interference relay 70T (Fig. 1) drops out to close its break contacts 70T2 (Fig. 3). This results in closure of the door of the elevator car A in the manner previously described. Such closure is accompanied by energization of the door safety relay DR (Fig. 1) and this relay closes its make contacts DR1.

The relay 70T also closes its break contacts 70T1 to complete the following circuit when the make contacts DR1 close:

L1, 70T1, X1, F2, 24, D, M, DR1, L2

The down switch D closes its make contacts D1 to release the elevator brake. In addition, make contacts D2 and D3 close to energize the field winding 16F with proper polarity for down travel of the elevator car. Closure of the make contacts D4 completes with the switch 21 and the break contacts E2 an energizing circuit for the speed relay V. This relay closes its make contacts V1 to shunt the resistor RE1. Consequently, the field winding 16F now is energized to produce full speed travel of the elevator car in the down direction.

Closure of the make contacts D5 establishes a holding circuit around the contacts 70T1 and X1. Opening of the break contacts D6 has no immediate effect on the operation of the system.

The running relay M closes its make contacts M1 and M2 without immediately affecting the operation of the system. Closure of the make contacts M3 energizes and picks up the non-interference relay 70T. Closure of the make contacts M4 (Fig. 2), opening of the break contacts M5 and closure of the make contacts M6 (Fig. 3) has no immediate effect on the operation of the system.

The energized non-interference relay 70T opens its break contacts 70T1 (Fig. 1) and 70T2 (Fig. 3) without immediately affecting the operation of the system.

The elevator car A now proceeds down towards the first floor. As the elevator car nears the first floor the brush bb engages the contact segment b (Fig. 2) to complete the following circuit:

L1, 1CR1, b1, bb, X4, T, M4, L2

As a result of its energization, the car-call stopping relay T closes its make contacts T1 (Fig. 1) to complete with the make contacts M1 an energizing circuit for the relays G, E and F. The relay G establishes a holding circuit around the contacts T1 by closing its make contacts G1.

As a result of further approach toward the first floor by the elevator car A, the inductor slow-down relay E comes into alignment with the inductor plate DEP for the first floor. This completes a magnetic circuit which results in opening of the break contacts E2 to deenergize the speed relay V. The speed relay V opens its make contacts V1 to introduce the resistor RE1 in series with the generator field winding 16F. The reduction in energization of the field winding slows the elevator car A to a landing speed.

The further approach of the elevator car A to the first floor brings the inductor stopping relay F into alignment with the inductor plate DFP for the first floor. This completes a magnetic circuit which results in opening of the break contacts F2 to deenergize the down switch D and the running relay M.

The down switch D opens its make contacts D1 to deenergize the brake coil 17 and permit reapplication of the spring-applied brake. In addition, the make contacts

D2 and D3 open to deenergize the field winding 16F. The elevator car A now stops accurately at the first floor.

The down switch also opens its make contacts D4 and D5 without immediately affecting the operation of the system. The closure of the break contacts D6 prepares the up-direction relay W for energization.

The running relay M upon deenergization opens its make contacts M1 to deenergize the relays G, E and F and these relays consequently reset without immediate effect on the operation of the system. Opening of make contacts M2 has no immediate effect on the operation of the system.

The opening of the make contacts M3 results in deenergization of the non-interference relay 70T and this relay starts to time out.

Opening of the make contacts M4 (Fig. 2), interrupts the energizing circuit for the car-call stopping relay. It will be assumed further that as the elevator car stops the brush bb passes slightly beyond the contact segment b1.

Closing of the break contacts M5 and opening of the make contacts M7 (Fig. 3) have no immediate effect on the operation of the system.

Referring to Fig. 3, the opening of the make contacts M6 interrupts the energization of the door-controlled relay 45 and this relay operates in the manner previously discussed to open the door of the elevator car A.

As the elevator car A reaches the first floor, the limit switches 21, 24 and 26 (Fig. 1) open and the limit switches 33 (Fig. 3) and 35 also open. The opening of these limit switches has no effect on the operation of the system with the exception that the opening of the limit switch 26 (Fig. 1) deenergizes the down-direction relay X. This relay opens its make contacts X1 without immediately affecting the operation of the system. However closure of the break contacts X2 completes the following circuit:

L1, D6, X2, J2, W, 25, L2

Opening of the make contacts X3 (Fig. 2) occurs shortly before the make contacts W3 close and consequently the car-call registering relay 1CR resets to open its make contacts 1CR1. Opening of the make contacts X4, X5 and X6 has no immediate effect on the operation of the system.

The up-direction relay W is now energized and closes its make contacts W1, opens its break contacts W2, closes its make contacts W3 (Fig. 2), W4, W5, W6 and W7 (Fig. 3) to prepare the elevator car for up travel.

Next it will be assumed that both of the elevator cars A and B are providing non-attendant elevator service and that both of the elevator cars A and B are displaced from the first floor when the switch 36 (Fig. 3) is operated to deenergize the bank transfer relay N. In response to its deenergization, the bank transfer relay opens its make contacts N1 and N2. However, the car transfer relays TR and BTR continue to be energized through their associated holding circuits. Attendants are present on the first floor for the purpose of entering the elevator cars when they are placed on attendant operation.

The elevators continue in non-attendant operation in the manner set forth in the preceding discussion until the elevator cars reach the first floor. It will be assumed that the elevator car A is the first to reach the first floor.

As the elevator car A reaches and stops at the first floor in the manner discussed above, the limit switch 35 (Fig. 3) opens to deenergize the car transfer relay TR. This relay closes its break contacts TR1 (Fig. 1) to maintain the energization of the non-interference relay 70T. Consequently, the non-interference relay 70T is no longer under the control of the running relay contacts M3.

Since the non-interference relay 70T is continuously energized, the break contacts 70T remain open and do not control the energization of the relays U, D and M. In addition, the break contacts 70T2 (Fig. 3) remain open and do not exercise control over the door control relay 45.

The car transfer relay TR also closes its break contacts TR2 (Fig. 1) to place the manual start relay 80 under the control of the car switch 80S.

In this case, when the car attendant desires to move the elevator car A from any floor at which it is stopped, he operates the car switch 80S to complete with the contacts TR2 an energizing circuit for the manual start relay 80. This relay closes its make contacts 80-2 (Fig. 3) to complete with the switch 31 an energizing circuit for the door control relay 45. This relay operates in the manner previously discussed to close the elevator car door.

In addition, the manual start relay 80 closes its make contacts 80-1. Since these contacts are in parallel with the contacts 70T1, they operate in the manner previously discussed for the contacts 70T1 to start the elevator car from a floor at which it is stopped. Consequently, the operation of the car transfer relay TR places the elevator car A under the control of the manual start relay 80 rather than under the control of the non-interference relay 70T1. It should be noted that the transfer of the elevator car A does not occur until the elevator car reaches the first floor.

It will be assumed that shortly after the elevator car A reaches the first floor, the elevator car B reaches the first floor. In an analogous manner the elevator car B on reaching the first floor opens the switch B35 (Fig. 3) to interrupt the holding circuit for the car transfer relay BTR. This relay closes its break contacts BTR1 (Fig. 1) to maintain a continuous energizing circuit for the non-interference relay B70T. In addition the break contacts BTR2 close to place the manual start relay B80 under the control of the car switch B80S. Thereafter the starting of the elevator car B from the first floor is under the control of the car attendant through operation of the car switch B80S rather than under the control of the non-interference relay B70T.

If desired, make contacts (not shown) of the running relays M and BM may be employed for shunting the limit switches 35 and B35 respectively in the same manner illustrated for the limit switches 33 and B33.

The sequence for removing one of the elevator cars from service now will be considered. It will be assumed that both of the elevator cars A and B are providing automatic operation and that both of the elevator cars are displaced from the first floor. At this stage the switch 32 (Fig. 3) is opened for the purpose of removing the elevator car A from service.

Since the elevator car A is displaced from the first floor, the limit switch 33 is closed and the in-service switch IS continues to be energized through the switch 33 and the contacts IS3. When the elevator car A reaches and stops at the first floor, it opens the switch 33 and the contacts M7 to interrupt the energization of the in-service switch IS. The in-service switch now opens its make contacts IS1 (Fig. 2) to prevent response of the elevator car to registered floor calls. In addition, make contacts IS2 (Fig. 3) open to prevent energization of the high-call reversal relay J. Opening of the make contacts IS3 prevents energization of the in-service switch IS until the manually-operable switch 32 again is operated.

Opening of the make contacts IS4 has no immediate effect on the operation of the system for the reason that the car transfer relay TR continues to be energized through its holding circuit.

The elevator car A continues in non-attendant operation until it reaches the first floor and opens the switch 35 to deenergize the car transfer relay TR. This relay operates in the manner previously discussed to close its break contacts TR1 (Fig. 1) for the purpose of continuously energizing the non-interference relay 70T. It also closes its break contacts TR2 to place the manual start relay 80 under the control of the car switch 80S. Consequently, the starting of the elevator car from a floor at which it is stopped now is initiated by operation of

the car switch 80S by the car attendant who enters the elevator car A at the first floor.

It should be noted that although the elevator car A does not respond to registered floor calls, it does respond to registered car calls. Consequently, the elevator car A is now under the full control of the car attendant.

Although the invention has been described with reference to certain specific embodiments thereof, numerous modifications falling within the spirit and scope of the invention are possible. Consequently, the specific embodiments herein disclosed are to be interpreted in an illustrative rather than in a limiting sense.

We claim as our invention:

1. In an elevator system, a structure having a plurality of floors including a transfer floor at which a transfer operation is to be effective, an elevator car, means mounting the elevator car for movement relative to the structure to serve the floors, motive means for moving the elevator car relative to the structure, control means operable for controlling the motive means to move the elevator car relative to the structure and to stop the elevator car at predetermined floors, automatic operating means for automatically initiating an operation of the control means, manual operating means for initiating an operation of the control means, and transfer means selectively operable for transferring the control means from control by one to control by the other of said operating means, said transfer means being effective after an operation thereof to complete said transferring only when the elevator car is adjacent said transfer floor regardless of the position of the elevator car at the time the transfer means is operated.

2. In an elevator system, a structure having a plurality of floors including a transfer floor at which a transfer operation is to be effective, an elevator car, means mounting the elevator car for movement relative to the structure to serve the floors, motive means for moving the elevator car relative to the structure, call registering means for registering calls for floors served by the elevator car, control means operable in cooperation with the motive means and the call registering means for moving the elevator car and for stopping the elevator car at floors for which calls are registered by the call registering means, automatic operating means for operating the control means to initiate movement of the elevator car away from a floor at which it is stopped, manual operating means actuatable from within the elevator car for operating the control means to initiate movement of the elevator car away from a floor at which it is stopped, and transfer means manually operable for transferring the control means from control by one to control by the other of said operating means, said transfer means permitting completion of said transferring only when the elevator car is stopped at said transfer floor regardless of the position of the elevator car at the time the transfer means is operated.

3. In an elevator system, a structure having a plurality of floors, an elevator car, means mounting the elevator car for movement relative to the structure to serve the floors, motive means for moving the elevator car relative to the structure, call registering means for registering calls for floors served by the elevator car, control means operable in cooperation with the motive means and the call registering means for moving the elevator car and for stopping the elevator car at floors for which calls are registered by the call registering means, time-responsive means for operating the control means to initiate movement of the elevator car away from a floor at which it is stopped, manual operating means actuatable from within the elevator car for operating the control means to initiate movement of the elevator car away from a floor at which it is stopped, and transfer means manually operable for transferring initiation of operation of the control means from control by the time-responsive means to control by said manual operating means, said transfer means including means permitting completion of said transferring only

when the elevator car is adjacent a predetermined one of the floors.

4. In an elevator system, a structure having a plurality of floors, an elevator car, means mounting the elevator car for movement relative to the structure to serve the floors, motive means for moving the elevator car relative to the structure, first call registering means operable within the elevator car for registering calls for floors served by the elevator car, second call registering means operable from the floors served by the elevator car for registering calls for elevator service, control means operable in cooperation with the motive means and the call registering means for moving the elevator car and for stopping the elevator car at floors for which calls are registered by the call registering means, time-responsive means for operating the control means to initiate movement of the elevator car away from a floor at which it is stopped, manual operating means actuatable from within the elevator car for operating the control means to initiate movement of the elevator car away from a floor at which it is stopped, and transfer means manually operable for transferring initiation of operation of the control means from control by the time-responsive means to control by said manual operating means, said transfer means including means permitting completion of said transferring only when the elevator car is stopped at a predetermined one of the floors and means responsive to such transferring for modifying the response of the elevator car to calls registered by the call registering means.

5. In an elevator system, a structure having a plurality of floors, an elevator car, means mounting the elevator car for movement relative to the structure to serve the floors, motive means for moving the elevator car relative to the structure, control means operable for controlling the motive means to move the elevator car relative to the structure and to stop the elevator car at predetermined floors, first operating means for controlling the control means in accordance with a first mode of operation, second operating means for controlling the control means in accordance with a second mode of operation, said elevator car in each of said modes being conditioned to stop at predetermined floors while set for travel in the given direction with the elevator car serving only one of the floors at each stop of the elevator car, and transfer means effective for transferring the control means from control by one to control by the other of said operating means only when the elevator car occupies substantially a predetermined position relative to the structure.

6. In an elevator system, a structure having a plurality of floors, a plurality of elevator cars, means mounting the elevator cars for movement relative to the structure to serve the floors, motive means for moving the elevator cars relative to the structure, control means operable for controlling the motive means to move the elevator cars relative to the structure and to stop the elevator cars at predetermined floors of the structure, automatic operating means for automatically initiating an operation of the control means to move each of the elevator cars from one of the floors of the structure at which the associated elevator car has stopped, manual operating means operable within each of the elevator cars for initiating an operation of the control means to move the associated elevator car from one of the floors of the structure at which such last-named associated elevator car has stopped, and transfer means selectively operable for transferring the control means from one to the other of said operating means, said transfer means being effective to complete said transferring of one of the elevator cars only when such last-named elevator car is adjacent a predetermined one of the floors.

7. In an elevator system, a structure having a plurality of floors, a plurality of elevator cars, means mounting the elevator cars for movement relative to the structure to serve the floors, motive means for moving the elevator cars relative to the structure, first call registering means

operable within each of the elevator cars for registering calls for floors served by the associated elevator car, second call registering means operable from the floors for registering calls for floors served by the elevator cars, control means operable in cooperation with the motive means and the call registering means for moving each of the elevator cars and for stopping each of the elevator cars at each of the floors approached by the elevator car for which a call is registered by the call registering means which may be answered by such elevator car, automatic operating means for automatically initiating operation of the control means to move each of the elevator cars from one of the floors at which the elevator car has stopped, manual operating means operable within each of the elevator cars for initiating an operation of the control means to move the associated elevator car from one of the floors of the structure at which such last-named elevator car has stopped, and transfer means selectively operable for transferring the control means from one to the other of said operating means for at least one of the elevator cars, said transfer means being effective to complete said transferring of one of the elevator cars only when the last-named elevator car is stopped at a predetermined one of the floors.

8. In an elevator system, a structure having a plurality of floors, a plurality of elevator cars, means mounting the elevator cars for movement relative to the structure to serve the floors, motive means for moving the elevator cars relative to the structure, first call registering means operable within each of the elevator cars for registering calls for floors served by the associated elevator car, second call registering means operable from the floors for registering calls for floors served by the elevator cars, control means operable in cooperation with the motive means and the call registering means for moving each of the elevator cars and for stopping each of the elevator cars at each of the floors approached by the elevator car for which a call is registered by the call registering means which may be answered by such elevator car, automatic operating means for automatically initiating operation of the control means to move each of the elevator cars from one of the floors at which the elevator car has stopped, manual operating means operable within each of the elevator cars for initiating an operation of the control means to move the associated elevator car from one of the floors of the structure at which such last-named elevator car has stopped, and transfer means selectively operable for transferring the control means from one to the other of said operating means for all of the elevator cars, said transfer means being effective to complete said transferring of any of said elevator cars only when the elevator car-to-be-transferred is stopped at a predetermined one of the floors.

9. In an elevator system, a structure having a plurality of floors, a plurality of elevator cars, means mounting the elevator cars for movement relative to the structure to serve the floors, motive means for moving the elevator cars relative to the structure, first call registering means operable within each of the elevator cars for registering calls for floors served by the associated elevator car, second call registering means operable from the floors for registering calls for floors served by the elevator cars, control means operable in cooperation with the motive means and the call registering means for moving each of the elevator cars and for stopping each of the elevator cars at each of the floors approached by the elevator car for which a call is registered by the call registering means which may be answered by such elevator car, automatic operating means for automatically initiating operation of the control means to move each of the elevator cars from one of the floors at which the elevator car has stopped, manual operating means operable within each of the elevator cars for initiating an operation of the control means to move the associated elevator car from one of the floors of the structure

at which such last-named elevator car has stopped, transfer means selectively operable for transferring the control means from one to the other of said operating means for all of the elevator cars, auxiliary transfer means operable in cooperation with the first-named transfer means for transferring the control means from one to the other of said operating means for certain only of the elevator cars, said transfer means being effective to complete said transferring of any of said elevator cars only when the elevator car-to-be-transferred is stopped at a predetermined one of the floors.

10. In an elevator system, a structure having a plurality of floors, a plurality of elevator cars, means mounting the elevator cars for movement relative to the structure to serve the floors, motive means for moving the elevator cars relative to the structure, first call registering means operable within each of the elevator cars for registering calls for floors served by the associated elevator car, second call registering means operable from the floors for registering calls for floors served by the elevator cars, control means operable in cooperation with the motive means and the call registering means for moving each of the elevator cars and for stopping each of the elevator cars at each of the floors approached by the elevator car for which a call is registered by the call registering means which may be answered by such elevator car, time-responsive operating means for automatically initiating operation of the control means to move each of the elevator cars from one of the floors at which the elevator car has stopped, manual operating means operable within each of the elevator cars for initiating an operation of the control means to move the associated elevator car from one of the floors of the structure at which such last-named elevator car has stopped, and transfer means selectively operable for transferring the control means from control by the time-responsive operating means to control by said manual operating means, said transfer means including means permitting completion of said transferring only when the elevator car is stopped at a predetermined one of the floors.

11. In an elevator system, a structure having a plurality of floors, a plurality of elevator cars, means mounting the elevator cars for movement relative to the structure to serve the floors, motive means for moving the elevator cars relative to the structure, first call registering means operable within each of the elevator cars for registering calls for floors served by the associated elevator car,

second call registering means operable from the floors for registering calls for floors served by the elevator cars, control means operable in cooperation with the motive means and the call registering means for moving each of the elevator cars and for stopping each of the elevator cars at each of the floors approached by the elevator car for which a call is registered by the call registering means which may be answered by such elevator car, time-responsive operating means for automatically initiating operation of the control means to move each of the elevator cars from one of the floors at which the elevator car has stopped, manual operating means operable within each of the elevator cars for initiating an operation of the control means to move the associated elevator car from one of the floors of the structure at which such last-named elevator car has stopped, and transfer means selectively operable for transferring the control means from control by the time-responsive operating means to control by said manual operating means, said transfer means including means permitting completion of said transferring only when the elevator car is adjacent a predetermined one of the floors, and means responsive to said transferring for modifying the response of the elevator cars to calls registered by said call registering means.

25 12. In an elevator system, a structure having a plurality of floors, a plurality of elevator cars, means mounting the elevator cars for movement relative to the structure to serve the floors, motive means for moving the elevator cars relative to the structure, control means operable for controlling the motive means to move the elevator cars relative to the structure and to stop the elevator cars at predetermined floors of the structure, first operating means for controlling the control means in accordance with a first pattern of operation, second operating means for 30 controlling the control means in accordance with a second pattern of operation, each of said elevator cars in each of said patterns being conditioned to stop at predetermined floors while set for travel in a given direction with each of the elevator cars serving only one of the floors at each 35 stop, and transfer means operable for transferring the control means from control by the first operating means to control by the second operating means, said transfer means being effective for said transferring for each of the elevator cars as each of the elevator cars reaches a predetermined 40 position relative to the structure.
